UNITED STATES PATENT OFFICE.

WILLIAM H. MORENUS, OF LAKE VIEW, IOWA, ASSIGNOR TO AUSTIN MANUFACTURING COMPANY, OF CHICAGO, ILLINOIS, A CORPORATION OF ILLINOIS.

DEFLECTOR FOR ELEVATING GRADERS.

No. 903,155.

Specification of Letters Patent.

Patented Nov. 3, 1908.

Original application filed August 2, 1907, Serial No. 386,713. Divided and this application filed January 11, 1908.
Serial No. 410,362.

To all whom it may concern:

Be it known that I, WILLIAM H. MORENUS, a citizen of the United States of America, and resident of Lake View, Sac county, 5 Iowa, have invented a certain new and useful Improvement in Deflectors for Elevating Graders, of which the following is a specification.

This is a division of my prior application 10 Number 386,713, filed August 2, 1907, for improvement in deflectors for ditching and grading machines, wherein I have claimed my invention broadly.

In the present application, I have dis- 15 closed and claimed an improved form of the deflector, in which the same is adjustably supported on the upper end of the elevator of a ditching and grading machine, and held in position by a yoke which can be ad- 20 justed back and forth to vary the angle or position of the deflector, whereby the soil can be discharged in different directions, and at a varying distance from the plow by adjusting the yoke and deflector to differ- 25 ent positions, according to requirements, as will hereinafter more fully appear.

In the accompanying drawings,—Figure 1 is a side elevation of the upper end of the elevator of an elevating grader, or of a 30 ditching and grading machine, showing the same equipped with a deflector embodying the principles of my invention. Fig. 2 is a plan of the structure and devices shown in Fig. 1. Fig. 3 is a view similar to Fig. 1, 35 illustrating another form of my invention. Fig. 4 is a perspective of the yoke, shown in Fig. 1.

As shown in Figs. 1, 2 and 4, the elevator A may be of any suitable known or ap- 40 proved construction. As illustrated, said elevator comprises a frame or body a, pro- vided with a traveling belt or conveyer a¹, which latter runs over an upper roller or rotatable member a². Said rotatable mem- 45 ber is mounted upon a shaft or journal which is supported in bearings a³, as shown in the drawings. The deflector B is disposed in position to receive the soil from the upper end of the elevator, and to throw the same 50 downwardly and inwardly, thus causing the soil to discharge under the elevator. A yoke b holds the upper end of the deflector in position, and the arms b¹ serve to support the said deflector. The arms b¹ are pro-

vided with bolt openings b² and the frame 55 of the elevator is provided with bolt open- ings b³. A pivot b⁴ serves to swingingly support the deflector on the arms b¹, in the manner shown. Pivots b⁵ are adapted to en- 60 gage the bolt openings b³, and to thereby 65 adjustably secure the arms b¹ on the ele- 70 vator. It will be seen that these arms b¹ rest upon the bearings a³ of the elevator structure. Pivots b⁶ are employed for 75 swingingly securing the yoke b to the arms b¹, these pivots being adapted to engage in one of the bolt openings b², thus providing 80 for relative adjustment between the yoke and the arms for the purpose of properly positioning the deflector. Said deflector is 85 easily applied and removed, and serves to effectually turn the soil back under the ele- 90 vator.

In Fig. 3, the elevator A has the usual 95 frame a, and the belt a¹, together with the roller or rotary member a² and the bearings a³, as previously described. In this case, however, the deflector C is disposed in position to receive the soil from the upper end of the elevator, and to deliver the same out- 100 wardly and away from the elevator. The yoke c is adapted to hold the outer or lower end of the deflector in position, and the arms c¹ support the inner or upper end of the deflector. The said arms have bolt openings c², 105 and the side portions of the elevator frame are provided with bolt openings c³. Pivots c⁴ are employed for swingingly securing the deflector on the said arms. The pivots c⁵ are applied for swingingly mounting the 110 arms c¹ in the bolt openings c³, whereby said arms can be adjusted to different positions on the elevator. It will be seen that said arms rest upon the bearings a³, as in the previous construction. Pivots c⁶ are employed 115 for swingingly securing the yoke c in place on said arms, and are adapted to engage the bolt openings c². In this way the said yoke can be adjusted along the said arms, in order 120 to change the position of the deflector. In operation the said deflector catches the soil and discharges the same outwardly and away from the elevator. A deflector thus 125 constructed is easily applied and removed, and serves for effectually discharging the soil 130 from the upper end of the elevator.

It will be seen that the deflector is mounted upon and carried by the outer end of the ele-

vator frame, so that movement or adjustment of the elevator does not change its relation to said deflector, as the deflector moves with the elevator, the deflector being supported entirely by the frame of the elevator.

What I claim as my invention is:

1. In a ditching and grading machine, a suitable elevator, a pair of arms secured to the frame of the elevator, a deflector mounted upon said arms, and a yoke adjustable on said arms and applied for holding the deflector in position.

2. In a ditching and grading machine, an elevator having hubs at its upper end, a pair of arms pivoted to the frame of the elevator and resting upon said hubs, a deflector pivoted on said arms, and a yoke pivoted on said arms and applied for holding the deflector in position.

3. In a ditching and grading machine, a suitable elevator, a pair of arms carried thereby, a deflector carried by said arms, a yoke carried by said arms and applied for holding the deflector in position to discharge 25 the soil outwardly and away from the machine.

4. The improved deflector for the upper end of the elevator of an elevating grader, or of a ditching and grading machine, and in combination with the arms and yoke for adjustably supporting the same in position to receive the soil from the endless traveling belt of said elevator, substantially as shown and described.

5. A ditching and grading machine provided with an elevator, a pair of arms pivoted on the side of the frame thereof and resting on the bearings of the upper end of said elevator, a deflector pivoted upon and

between said arms, and a yoke supported on 40 said arms and embracing the deflector to hold the same in position.

6. A ditching and grading machine provided with an elevator, a pair of arms supported upon and embracing the upper 45 end of said elevator, a deflector pivoted upon and between the outer ends of said arms, and a yoke supported on said arms and embracing the deflector to hold the same in position.

7. A ditching and grading machine provided with an elevator, a pair of arms adjustably supported upon and embracing the upper end of said elevator, a deflector pivoted upon and between the outer ends of 50 said arms, and a yoke adjustably supported on said arms and embracing the deflector to hold the same in position.

8. The combination, with the belt conveyer of a ditching and grading machine, of a deflector for the discharging end of said elevator, carried upon the frame thereof, and a yoke for holding the said deflector in position to discharge the soil in a direction transverse of the line of travel of said machine.

9. The combination, with the belt conveyer 65 of a ditching and grading machine, of a deflector for the discharging end of said elevator, pivoted upon and carried by the frame thereof, and an adjustable yoke for holding the said deflector in position to discharge the 70 soil in a direction transverse of the line of travel of said machine.

Signed by me at Chicago, Cook county, Illinois, this 18th day of December 1907.

WILLIAM H. MORENUS.
